104 Claims. (Cl. 12—37)

This invention relates to machines for use in the manufacture of boots and shoes and particularly to improved machines for pressing a sole and a shoe together to cause the sole to conform to the shape of and adhere to the shoe bottom, the illustrated machine being especially adapted for use in the manufacture of shoes in which cement alone is relied upon to provide permanent attachment of the sole to the shoe.

10 In cement attaching soles to shoes it is common practice at the present time to coat the flesh side of an outsole and the bottom of a lasted shoe with cement, and to mount them in a selected position on an inflatable pad. After the sole and 15 shoe have been properly positioned on the pad they are clamped to insure against movement relatively to each other or to the pad. The pad is then inflated to cause it to press against the sole to force the sole firmly against the shoe bottom and the pressure is maintained for a time long enough to allow the cement to set thoroughly, after which the pressure is released and the shoe with the sole attached is removed from the pad.

20 In order to speed up production while yet allowing sufficient time for the cement to set so that the shoes can be removed from the machine, it has been the practice in recent years to mount a plurality of pads on a machine constructed and 25 arranged to present each pad in turn at an operating station where a sole and a shoe may be mounted and clamped on each pad. The pads are caused to move past the operating station, usually with a stepwise motion and to progress 30 until they return to the operating station. The pressure is released as, or shortly before, each shoe reaches the operating station so that the shoe can be removed from the pad.

The shoes must remain under pressure until 35 the cement has set sufficiently to hold the soles in place, which takes from fifteen to thirty minutes with much of the pyroxylin cement now in commercial use. Since only a short time is ordinarily required for mounting and clamping 40 a sole and shoe on a pad, the rest of the pressing operation takes place while the pad is moving along in the machine and while other shoes are being positioned on other pads at the operating station. It will be seen from the above that, 45 unless a large number of pads are provided in the machine so that a considerable period of time will be consumed in mounting a corresponding number of shoes on successive pads after the first pad has left the operating station, the shoe on this 50 pad will have returned to the operating station

before the cement between the sole and the shoe bottom has had sufficient time to set properly.

Heretofore in machines which have been adapted to operate on a sole and shoe in the manner described, the inclusion of a large number of pads has frequently resulted in producing a huge, unwieldy structure which takes up a considerable amount of floor space. This is because the pads must not only be spaced apart sufficiently to allow for shoe-clamping mechanism of some sort to be mounted above each of the pads, but because there must also be enough space left over the pads to introduce and position a shoe and sole on each pad before the clamping mechanism is brought into engagement with the shoe. The shoe-clamping mechanisms or devices referred to are frequently mounted on pad boxes which carry the pads, thereby increasing the space occupied by each box so that a large number of boxes can not be conveniently positioned in close proximity to each other to obtain the compact arrangement of pads desired in a multiple-pad machine.

Important objects of this invention are to provide an improved machine for cement attaching soles to shoes which, while having a comparatively large number of fluid-filled pads, will be compactly arranged and yet will afford sufficient space at an operating station for convenient introduction and removal of a shoe and sole, to provide improved means for retaining a shoe and sole on each of a plurality of pads during a sole pressing operation, and to provide mechanism in a multiple-pad machine for correctly positioning a shoe and a sole relatively to each other on a fluid-filled pad.

With these objects in view, and in accordance with the present invention, the illustrated machine is provided with a plurality of pads arranged each to receive a sole and shoe, said pads being mounted in pad boxes which are positioned in close proximity to each other so that the bottom of one pad box may be utilized for holding a shoe on another or the next pad. In the illustrated machine the adjacent pads move in an endless series in a vertical plane perpendicular to a horizontal axis, each pad being presented in turn at an operating station where a sole and shoe may be positioned on its upper surface. As illustrated, each pad is mounted in a pad box carried on the outer extremity of an arm which is radially mounted on a stationary horizontal shaft and arranged to rotate about the shaft to present the pads successively at the operating station. The arrangement of the adjacent pads on radial arms which rotate in an endless series about a hori-

90

95

100

105

110

zontal axis permits a comparatively large number of pads to be utilized without causing undue bulkiness in the design of the machine. A space is provided between the arms at one point in the 5 series, in the present case at the operating station, to give an operator an opportunity to introduce a sole and shoe conveniently on a pad at the operating station.

In the illustrated machine, improved means is 10 provided for clamping a shoe and sole on each pad, said means being mounted on the bottom of each pad box and being constructed and arranged to engage a shoe mounted on the pad of another pad box. As illustrated herein the holding or 15 clamping means comprises a lever pivotally mounted on ears extending from the bottom surface of each pad box. Abutments carried by the lever are provided, one adapted to engage the forepart or toe portion of a shoe on a last mounted on an adjacent pad and another adapted to 20 engage the cone of the last. Preferably and as illustrated the toe abutment is adjustable relatively to the lever so as to enable the abutments to accommodate various sizes and shapes of lasts. 25 When a sole and shoe have been properly positioned on a pad at the operating station, the arm carrying the pad box above this station is arranged to be lowered by treadle controlled means into shoe-clamping position relatively to the shoe 30 on the pad at the operating station. The shoe on the pad at the operating station will thus be clamped by the abutments in the manner described, and the space at this station will be shifted from above the pad at the operating station to a position above the pad which is now in 35 shoe-clamping position and which is next to be lowered into the operating station. Thus it will be seen that while space is provided at the operating station to permit the removal of a shoe and 40 the introduction of another shoe on a pad presented at this station, there is no waste space between the pads while they are away from the operating station.

In cement attaching soles to shoes it is important 45 that the sole and shoe be located properly with respect to each other and that a proper extension of the sole be afforded at all parts of the periphery of the sole so that a minimum of edge trimming will be required. Accordingly, means 50 is provided in the illustrated machine for positioning a sole and shoe relatively to each other on a pad at the operating station, said means comprising a plurality of sole engaging feelers and shoe gages mounted on carriages located at opposite 55 sides of the operating station and preferably being constructed and arranged to move into and out of operative position over each pad as the pads are presented successively at the operating station. In order to provide a convenient 60 arrangement for mounting the positioning means to operate on successive pads, and in order that, as each pad leaves the operating station, the positioning means may be withdrawn from the path of movement of the pads, the pad boxes in the illustrated machine are located with 65 their longest axes parallel to each other and perpendicular to the path of movement of the pads so that each pad will be presented side on at the operating station. This arrangement permits the 70 positioning feelers and gages to be located at opposite ends of a pad box and to be moved simultaneously into and out of operative position over the toe and heel ends of each pad from opposite ends thereof and in a direction lengthwise of the 75 pad box.

The positioning means as illustrated herein, is adapted to remain in close engagement with the shoe and sole until they are secured in a selected position on a pad at the operating station, after which the feelers and gages will be automatically withdrawn to their inoperative positions so as not to interfere with the stepwise progression of the series of pads.

As used herein, the word "top," as applied to the pads in this specification and the accompanying claims, should be taken as referring to the shoe and sole supporting walls or surfaces of the pads regardless of whether such a wall or surface is further from the center of the earth than the opposite wall or surface of a pad, either at a particular instant or permanently, and the words "bottom," "over," "upper," "lower," etc., as applied to the pads and pad boxes, should be taken in a corresponding sense.

The above and other features of the invention including also novel means for admitting fluid under pressure to the pads, novel means for automatically restoring the pressure in and exhausting the fluid from the pads, and various details of construction and combinations of parts will now 100 be more particularly described by reference to the accompanying drawings and thereafter pointed out in the claims.

In the drawings,

Fig. 1 is a side elevation of a portion of the 105 machine embodying the present invention;

Fig. 2 is a view in front elevation of the structure shown in Fig. 1;

Fig. 3 is a front elevation showing certain rotary valve arrangements hereinafter described; 110 and

Fig. 4 is a sectional view, on the line 4—4 of Fig. 3.

The illustrated machine comprises a rectangular base 10 having upstanding columns 12, 14 at opposite sides thereof. A stationary shaft 16 passes transversely between the columns 12 and 14 and is secured in the upper ends of the columns. A series of arms (in the present instance thirty) are mounted on the stationary shaft 16 115 and are adapted to move around the shaft in an intermittent or stepwise manner. Each arm comprises two links 18 spaced apart along the shaft 16 and carrying at their outer ends a hollow metal box 20. The hollow box 20 has an open top and 120 is arranged to hold an inflatable hollow moulded-rubber pad 22 (see Figure 2), which has a flat bottom, vertical sides and a top so shaped that it will contact closely with the bottom of a shoe placed thereon. The length of the pad lies at 130 right angles to the length of the arm, and parallel to the axis of the stationary shaft 16, as shown in Figure 2.

In order to mount the arms on the stationary shaft 16 the two links 18, forming the sides of each arm, are connected at their inner ends by a horizontal bridge piece 24 which is adapted to be secured to a horizontal bar 26 of a yoke member 28 (see Figure 1), the yoke member having inwardly extending ears through which the stationary shaft 16 passes. It is to be understood that each arm is carried by a separate yoke and that there are, therefore, thirty similar yokes arranged on the stationary shaft. The inwardly extending ears of the yoke lie side by side along 140 the stationary shaft and, in order that the arms carried by the yokes may lie in a single plane at right angles to the axis of the shaft, the bridge pieces 24 which connect the inner ends of the links 18 are adjustable by slot and bolt 145 150

connections along the bars 26 of the yoke members. A shoe and sole may be mounted upon each pad 22 (in a manner hereinafter described) as the arm carrying the pad comes to a substantially horizontal position in front of an operator standing in the plane of rotation of the arms and facing the stationary shaft 16.

In order to assist the operator in positioning a sole and a shoe correctly on the upper surface 10 of a pad which has been presented at the operating station (i. e. the position indicated at A in Figure 1), positioning means similar to those disclosed in Letters Patent of the United States, No. 1,897,105 granted Feb. 14, 1933 on an application filed in the name of Milton H. Ballard, are provided in the illustrative machine. Such means comprises a pair of carriages indicated at 15 30 and 32 which carry respectively the forepart and heel end positioning mechanism, the carriage 30 and its forepart locating mechanism being similar to those described in the specification above-mentioned and the carriage 32 and the heel end positioning mechanism carried thereby being similar to those disclosed in application for Letters Patent of the United States, Serial No. 414,516 filed Dec. 16, 1929 in the name 20 of Sidney J. Finn. The carriages 30, 32 are positioned on outwardly inclined guideways 34, 36 which are secured to upwardly extending columns 38, 40 projecting from the front end of the base 10 and spaced apart sufficiently to allow the pads on the arms to pass between them as the arms move around the stationary shaft. The guideways 34, 36 extend outwardly to the right 25 and left of the machine and are arranged at such a height that when a pad is in work-receiving position at the operating station the carriages 30, 32 may be caused to move inwardly on their guideways toward opposite ends of the upper surface 40 of the pad.

The carriage 30 which approaches the pad from the left carries elements having feelers 42 to find the toe and sides of the forepart of a sole positioned on a pad at the operating station and gage members 44 to engage the toe and sides of the forepart of a shoe to locate the latter relatively to the former and to hold both the shoe and sole in position on the pad. The carriage 32 which approaches the pad from the right carries elements similar to those disclosed in application for Letters Patent of the United States Serial No. 414,516, mentioned above, having feelers 46 adapted to find the heel end of a sole and having gage members 48 adapted to engage the opposite sides of the heel end of a shoe. The shoe-engaging members of the elements on the carriage 32 are released to take up their positions by a hand lever 50 after the feelers have engaged the sole. The two carriages 30 and 32 are held outwardly along the guideways 34 and 36 except when they are actually in use, by mechanism hereinafter described, so as not to obstruct rotary movement of the arms about the stationary shaft 16. When the operator wishes 55 to make use of the positioning means to assist him in positioning a shoe and sole on a pad at the operating station, he places a sole centrally on the pad and then trips a treadle 52 to release a pair of weights 53 which, in falling, cause the carriages 30 and 32 to approach opposite ends of the pad to bring the feelers 42 and 46 into contact with the upper surface of the pad and into engagement with the sole. As the sole-engaging feelers 42 contact with the toe end and sides of the sole, they position the

shoe-engaging members 44 in such a position relatively to the sole that a shoe placed between the shoe-engaging members will be correctly located relatively to the toe end of the sole. Similarly, after the sole-engaging feelers 46 have engaged the heel end of the sole, the shoe-positioning gage members 48, when released by depression of the handle 50, assume correct positions relatively to the edges of the sole and will position the shoe relatively to the sole at the heel end. Mechanism, hereinafter described, connects the carriages 30, 32 with means for rotating the arms about the axis of the stationary shaft, this mechanism also withdrawing the carriages outwardly along their guideways 34, 36 away from the pad after pressure has been applied to the shoe by inflation of the pad. The sole and shoe engaging elements will, therefore, be withdrawn from over the pad to allow the pad to move downwardly away from work-receiving position at the operating station and to allow the pad which is immediately above to move downwardly into work-receiving position.

The outer face of the bottom of the metal box 20 which is mounted at the outer end of each arm, has shoe engaging devices secured to it which comprise a member 54 adapted to press against the cone of a last in a shoe on the pad carried by the arm which lies closest to the bottom of the box, and a member 56 adapted to 100 press against the forepart of the shoe.

The member 54 which is adapted to engage the cone of the last has a roughened under face and is pivoted at one end of a slotted link 58 which in turn is pivoted about midway of its length on a pivot pin 60 passing parallel to the length of the arm between ears on the bottom of the box. Also pivoted on the pin 60 is another link 62 which extends downwardly to the left and carries at its lower end a depending lug on which is mounted, with a certain freedom of movement, the member 56 which is adapted to press against a shoe just rearwardly of the toe portion. A spring 64 tends to lift the link 62 toward the bottom of the box and 115 an adjustable stud 66 passing through the link 62 butts against the under side of the left end of the link 58 and limits to an adjustable extent the relative heights of the two abutments 54 and 56. When a shoe and sole have been 120 correctly positioned on a pad which is in work-receiving position, the operator can, as hereinafter described, cause the arm above the shoe to be lowered until the shoe engaging members 54 and 56 carried by the arm engage the shoe 125 and hold it against the pad on which it has been placed.

Means are provided in the illustrative embodiment to cause each arm, when it has been lowered toward an arm which is in work-receiving 130 position, to become latched to that arm in order that a shoe mounted on the latter arm may be retained against movement during the pressure applying operation.

To this end a transverse rod 68 (see Figure 1 140 particularly) passes parallel to the stationary shaft 16, across the links 18 of each arm and on each end of the rod is rigidly secured a latch member 70. When the arm above the operating station has been brought down into shoe-jacking 144 position, the latch members 70 on the arm at said station engage pins 72 (see Figure 1) projecting from the arm above and latch the arms together. The forward portions of the tops of the latches 70 are inclined or beveled off rearwardly as 150

shown in Figure 1 so that when an arm descends toward an arm which is at the operating station, the pins 72 on the descending arm will strike the rearwardly sloping edges on the tops of the latches 5 and cam the latches rearwardly until slots 74 in the forward faces of the latches come into line with the pins 72, whereupon springs 73 connected to the latches will urge them forwardly to latch over the pins. Thus, an arm at the operating 10 station which has had a shoe and sole assembled on its pad will become latched to the arm above it and the shoe, having been engaged by the shoe engaging members 54, 56 carried by the upper arm, will be held rigidly while the pad is inflated 15 to press the sole against the shoe bottom.

All the arms are normally coupled to neighboring arms by their latches 70, except the arm which is at the operating station and the arm immediately above it at that time. These arms 20 are not latched to each other while the work-positioning operation is in progress, although they are latched to the arms on their opposite sides. Therefore, when the arm which is immediately 25 above the arm in work-receiving position at the operating station is brought down into work-jacking position relatively to a shoe on the latter arm, it must be uncoupled from the arm above it and be coupled to the arm at the operating station. The mechanism by which each arm in 30 turn is brought down into work-jacking position comprises a treadle operated lever 76 which is pivoted at 78 to a casing 80 secured to the column 12. The pivot 78 for the lever 76 is, as seen in Figure 1, nearer the front of the machine than 35 the stationary shaft 16 and the lever 76 has a rearwardly projecting arm 82 extending beyond the shaft and provided at its rear end with a balance weight 84 the purpose of which will be hereinafter explained. A trip-piece 86, comprising a 40 lever with a pivotally mounted nose 88 at its forward end, is secured on the forward end of the lever 76. The trip-piece 86 is mounted on a horizontal pivot 90 and is connected, forwardly of its pivot, to a treadle 92 by a treadle rod 94. When 45 an arm is at the operating station, the forward end or nose 88 of the trip-piece 86 is arranged to end above the end of a rearwardly projecting finger 96 formed on the latch 70 at the right side of that arm which is immediately above the arm 50 at the operating station. When a shoe and its sole have been assembled on the pad of the arm at the operating station, the operator may depress the treadle 92 to cause the trip-piece 86 to be lowered about its pivot 90 and, by engagement with the rearwardly projecting finger 55 on the latch 70 on the arm which is immediately above the arm at the operating station, may cause both latches on that arm (since they are both rigidly secured to the transverse rod 68 on which 60 they are mounted) to move out of engagement with the pins 72 on the next highest arm. In order that the trip-piece 86 may be moved downwardly to trip the latches without swinging the 65 weighted lever 76, lost motion (consisting of a pin on the lever which enters an arcuate slot in the trip-piece) is provided between the trip-piece and the lever. Movement of the trip-piece and tripping the latches on the arm above the operating 70 station will take up this lost motion and further depression of the treadle 92, after the latches have been tripped, will cause the weighted lever 76 to swing downwardly. The pivotally mounted nose 88 on the trip-piece may be depressed against 75 a spring to permit the fingers 96 of the latches 70

on the arms above the trip-piece to be lowered into position directly under the nose of the trip-piece. Each arm has a lug 98 projecting from the right hand link 18 and the weighted lever 76 has a similar lug 100 projecting laterally from 80 its inner side. The weight on the rear end of the lever 76 causes the forward portion of this lever normally to rise until the lug 100 thereon contacts with the lower face of the lug 98 projecting from the arm above the work-receiving position. The arm remains in this position while the trip-piece is being moved to trip the latches to disconnect this arm from the arm above. The weight 84 upon the rear end of the treadle-operated lever is somewhat greater than is necessary to balance both the lever and the arm which it supports, by reason of the engagement of the lugs on the lever and arm after the latches have been tripped and, therefore, when an arm has been unlatched from the arm above, it falls only at the speed at which the weighted lever is drawn down by the treadle 92.

As stated above, the pivot 78 for the lever 76 is nearer the front of the machine than the shaft 16 which forms the pivot about which the arms 100 rotate. Consequently, the lug 100 on the lever 76 describes an arc the radius of which is considerably shorter than the radius of the arc described by the lugs 98 on the arms. As the arms are lowered by downward movement of the lever 76, the 105 above arrangement causes the lug 100, which describes the smaller arc, to slide inwardly along the lug 98 on each arm until it moves out of the path of the lug 98. The lever 76 is then free to be carried upwardly by the weight 84 until it 110 reaches its inoperative position as shown in Fig. 1. A dash pot is provided as shown in Fig. 1 to cushion the upward movement of the lever 76.

It will be understood, therefore, that when work is being positioned in the machine each of the 115 thirty arms is latched to the arm on either side of it with the exception of the arm which is at the operating station and the arm immediately above it. These arms, however, although not latched to each other are latched to the arms immediately 120 below and above them respectively.

Means is provided in the illustrative machine to move the arms in a body, in such a manner (i. e. in a counterclockwise direction as seen from the right-hand side of the machine) as to carry a 125 shoe which has been jacked, downwardly from the operating station to bring the pad on the arm which is next above the operating station into position to receive a shoe. For this purpose each arm has projecting outwardly from its right side, 130 approximately half way along its length, a round steel pin 102. A notched steel disc 104 is provided which is adapted to be rotated to engage the pins successively in order to rotate the arms. The notched disk 104 is mounted in a space between 135 the arms and the column 12 at the right side of the machine and is secured to the left end of a short horizontal shaft 106 mounted in bearings in the column 12. On the other end of this shaft is mounted a worm wheel 108 (see Figure 1) and 140 a shaft 110, passing forwardly and rearwardly of the machine through the column 12 below the shaft 106, carries a worm 112 which meshes with the worm wheel 108. A swash plate clutch 114 (of the same general nature as that disclosed in 145 United States Letters Patent No. 1,124,620 granted January 12, 1915 on the application of Arthur E. Jerram) is mounted on the rear end of the worm shaft 110 and a pulley 115 associated with the clutch is driven by a belt 116 from an electric 150

motor 118 situated on the base of the machine. A smaller notched plate 120, associated with a trip device 122 for the clutch 114, is also mounted on the shaft 106 close to the plate 104. The two notched plates 104 and 120 have the same number of notches around their peripheries (in the present instance seven) and a cam roll 124 mounted upon the upper end of a pivotally mounted bell crank lever 126 is arranged to run on the periphery of the smaller notched plate 120. A substantially horizontal arm of the bell crank lever 126 carries a stop which engages the trip device 122 for the swash plate clutch 114 and the arrangement is such that when the cam roll 124 on the upper end of the bell crank lever 126 enters a notch on the small notched plate 120, as the notched plates are rotated by the clutch 114, the trip device 122 is actuated to cause the clutch to be thrown out of driving engagement with the motor and into engagement with a brake, thus bringing the notched plates and the arms driven thereby to rest.

This condition applies as each of the arms comes successively to the operating station.

In order to trip the swash plate clutch 114 to cause rotation of the arms, a push lever 128 is provided which, however, operates first to put in motion driving mechanism for withdrawing the carriages 30, 32 from the pad which is then at the operating station. This driving mechanism comprises a second swash plate clutch 130 similar to that previously mentioned and also driven by a belt 132 from the electric motor 118, a trip device 134 for this clutch being coupled directly to the push lever 128 by a rod 136 and a lever 138. When the clutch 130 is engaged it operates through a worm 140 and worm wheel 142 to rotate a disc 144 mounted on a short transverse shaft 146 journaled in the base of the machine. The rotary disc 144 is provided with an eccentric pin 148 and has a single notch 150 in its periphery. An upwardly extending link 152 is pivotally mounted at its lower end on a transverse pin 154 secured to a parallel-linkage arrangement 156, 158 which supports the treadle 52 controlling the feeler-carrying carriages 30, 32. The upwardly extending link 152 has a slot 160 in its upper end which engages the eccentric pin 148 on the rotary disc 144.

Rearwardly of the link 152 is a straight double arm lever 162 which is mounted on a transverse pin 164 projecting from the machine base and which has an upwardly extending arm carrying a cam roll 166 against which the upwardly extending link 152 is adapted to strike as the link is oscillated about its pivot 154 by the rotation of the rotary disc 144 carrying the eccentric pin 148. A downwardly extending arm of the lever 162 is connected by a horizontal rod 168 to a bell crank lever 170 which is also coupled to the trip device 122 of the swash plate clutch 114 first-mentioned. A spring 172 located between a face on the machine frame and a collar on the horizontal rod 168 tends to urge the double arm lever 162 in a counterclockwise direction (as seen from the right side of the machine) to retain the trip device of the clutch 114 in a position in which the clutch is untripped. The above-described mechanism is so arranged that, when the operator wishes to move the pad on which he has assembled a shoe and sole away from the operating station and to bring an empty arm to this station, he moves the push lever 128 rearwardly and thus trips the swash plate clutch 130, which, through the slotted link 152 and eccentric pin

148 (which at this time rests in the bottom of the slot in the slotted link), immediately depresses the treadle 52 and withdraws the carriages 30, 32 and the members mounted thereon away from the pad. As the eccentric pin 148 moves around, it causes the upstanding link 152 to swing about its pivot 154 and to come into contact with the cam roll 166 on the double arm lever 162. The lever 162 is rocked about its pivot 164 to trip the first-mentioned clutch 114 which causes the notched plates 104 and 120 to rotate the arms carrying the pads. When the disc 144 has rotated through one complete revolution, the notch 150 in its periphery comes beneath a cam roll 174 on a horizontal lever 176 which is connected by a rod 178 to the trip device 134 of the clutch 130. The roll 174 is urged by a spring to enter the notch 150, thus causing the horizontal lever 176 to rock to throw out the clutch. The notches in the larger notched plate 104 aforementioned are spaced apart around its periphery so that successive notches engage pins 102 on successive arms as the latter are rotated about the stationary shaft 16 and, since all the arms are latched together, rotation of the larger notched plate causes the arms to move as a unit around the stationary shaft 16. As before stated, rotation of the arms continues until one of the notches on the smaller notched plate 120 comes beneath the cam roll 124 on the bell crank lever 126, whereupon the bell crank lever rocks and the clutch 114 is thrown out. Before the clutch has been thrown out in the manner described, however, the pad on the arm next above that which was last at the operating station will have been brought into work-receiving position at the operating station.

A safety device is provided which is arranged to prevent rearward movement of the push lever 128 to start the machine until after the lever 76 has been lowered to bring an arm into work jacking position relatively to a shoe on an arm at the operating station. The safety device comprises a substantially horizontal rod 238 pivoted on ears 240 formed on the lever 76 below its pivot 78. The other end of the rod extends through, and is supported by, a small opening in the push lever 128 and has a collar 242 secured to it. The collar is positioned in close proximity to the inner side of the push lever 128 to prevent rearward movement of the push lever. As the weighted lever 76 is swung about its pivot 78 and is moved downwardly to lower an arm into work jacking position, the rod 238 and the collar 242 are carried rearwardly thus allowing the push lever 128 to be moved rearwardly to trip the clutch 130.

After a shoe and sole have been placed on the pad and, with the aid of the positioning fingers carried on the carriages 30 and 32, have been positioned thereon relatively to each other, the treadle 92, connected to the weighted lever 76, may be depressed to cause the arm which is above the operating station to become unlatched from the arm next above it and to be lowered toward and latched to the arm which is now at the operating station, thereby clamping the shoe and sole on the pad in proper position for a pressure applying operation. Thus it will be understood that each arm in turn will be rotated in a series of steps by the driving mechanism described from the operating station (in which position a shoe and a sole will be assembled on the pad) downwardly past the operator and around the stationary shaft 16 until in turn it comes to a po-

sition above the operating station. When the arm has arrived at this position it will, after a shoe and sole have been positioned on the pad which is then at the operating station, be unlatched by the operator from the arm above and be brought down toward the arm at the operating station to become latched thereto. A further stepwise movement of the arms, due to further operation of the driving mechanism, will cause the arm referred to to descend to the operating station to permit the removal of the shoe thereon and for the introduction of another shoe and sole.

The mechanism described so far has been concerned solely with the construction of the work-carrying arms, the shoe- and sole-positioning means and the means for rotating the work-carrying arms. No means has yet been described for inflating the pads to cause a pressing operation to take place and, accordingly, such means will now be described. A source of compressed air, preferably at a pressure of about forty pounds per square inch, supplied for example by means of a rotary compressor, is connected by a pipe 180 (see Figure 2) to a small valve casing 182 mounted below the stationary shaft 16 on the column 14. Two branch pipes 184, 185 (see also Figure 3) lead from opposite sides of the valve casing 182 and communicate (through ducts in the column 14) with radial holes in the front and rear sides of the left end of the stationary shaft 16 where that end is supported in the column 14. The threaded holes lead into separate ducts 186, 188 (see Figure 4) formed parallel to the axis in the stationary shaft 16. A frusto-conical valve member 190 (hereinafter termed the valve) is rigidly secured to the stationary shaft 16 and is so located between the column 14 and the arms that a threaded neck 192 (see Figure 3), extending axially from its smaller end, butts against the inner side of the column 14, the larger end of the valve lying nearer the arms. The valve 190 has ports formed in it which run radially from its outer face to its inner face and these ports communicate with the two axial ducts in the stationary shaft 16. One of said ports (hereinafter termed the inlet port) shown at 194 in Figures 3 and 4, is arranged to supply fluid under pressure, such for example as compressed air, to each pad when it has reached the operating station and after a shoe and sole have been assembled on and jacked to the pad as described. The inlet port 194 communicates with the duct 186 and comprises a groove which extends axially along the outer face of the valve for about half the width of the valve. Another port (hereinafter termed the make-up port), shown at 196 in Figure 4 only, comprises a hollow threaded stem communicating with the duct 188 and arranged to supply compressed air to the pads during the time that the arms move from the operating station around to an exhaust position (hereinafter described), to replace any air that may escape from the pads during this period. The make-up port 196 leads into a rectangular cut-away portion or depression 198 sunk beneath the outer face of the valve 190. This cut-away portion extends around the underside of the valve for approximately one fifth of the periphery of the valve, its width being about half the width of the valve. Two similar cut-away portions 200, 202 are arranged symmetrically around the valve and communicate with the cut-away portion 198 by means of shallow grooves 204, joining them circumferentially of the valve.

The groove of the inlet port 194 is located on the peripheral face of the valve in the region between the two cut-away portions 200 and 202 as shown in Figures 3 and 4.

A frusto-conical sleeve 206 (hereinafter called the valve casing) is mounted on the valve 190 to rotate around it in company with the arms, the sleeve being mounted sufficiently tight on the valve to provide an air-tight fit between it and the valve 190. A thrust bearing 208 (Figure 3) containing a ball race is threaded on the neck 192 of the valve and bears against the smaller end of the frusto-conical valve casing 206, thus holding the latter in place on the valve. The valve casing has thirty radial bores 210 formed in it (one for each pad), the bores being arranged for convenience in two parallel rows as seen in Figure 3, and staggered with respect to each other, around the peripheral face of the valve casing. Each of the bores in the valve casing has screwed into its outer end a nipple which connects, by a short length of metal tubing 212 and a short length of flexible tubing 213, with a hollow rigid metal tube 214 (see Figure 2) which leads into one of the pads and is positioned along the side of the arm which carries that pad. The valve casing 206 is connected by a metal strap 207 to one of the arms 18 and moves around the valve 190 as that arm moves around the stationary shaft 16. The bores 210 in the valve casing are so arranged that they come into alignment, one at a time as the valve casing rotates, with the inlet port 194, in the valve, the valve casing being shown in Figures 3 and 4 in a position in which one of the ducts is just being brought into alignment with the inlet port. As the valve casing 206 rotates, the bores sweep over the rectangular cut-away portions 198, 200 and 202 which communicate with the make-up valve 196 and each bore 210, therefore, remains in communication with the air supply during the greater part of the rotation of the valve casing before the bore comes into exhaust position. As the valve casing rotates around the valve, each bore comes first into communication with the inlet port, at which time compressed air may pass from this port through the bore into a pad. The bore then comes into communication successively with the three connected cut-away portions from which compressed air may pass through the bore into the pad to supply any deficiency of air and to keep the pressure within the pad at the requisite value.

As has previously been stated, each pad-box carries on its underside shoe-retaining members 130 which engage a shoe on a pad on an adjacent arm and, although the adjacent arms are latched together while the pressing operation is taking place, they are unlatched before they reach the operating station. It therefore becomes desirable, after a pad has been inflated and has been rotated as a unit with the other arms about the stationary shaft as successive pads are presented at the operating station, that the pad be deflated when it reaches that position, above the operating station, at which the arm which carries it is to be unlatched from the arm next above it and brought down and latched to the arm which is at the operating station. In order that the pads may be deflated in succession as they reach the position immediately above the operating station, the valve 190 is provided, above the inlet port 194, with a third port 216 (hereinafter termed the exhaust port) with which the bores in the valve casing come into communication one by one as 150

the arms reach the position mentioned above. The exhaust port communicates with a third axial duct 218 in the stationary shaft 16 from which the compressed air, in exhausting from each pad as the arms successively reach the position indicated, is allowed to escape into the atmosphere. The exhaust port 216 comprises a circular passage passing radially from the inner face of the valve toward the outer face, the outer end of the circular passage entering an L-shaped groove sunk in the face of the valve as shown in Figure 3. The longer limb of the groove extends along the valve substantially at right angles to the end faces of the latter and the shorter limb extends upwardly around the valve away from the inlet port 194 and serves a purpose later to be explained.

The angular arrangements of the arms, the bores in the valve casing and the inlet and exhaust ports in the valve itself are as follows.

The angle between the center lines of the exhaust port 216 and inlet port 194 in the valve is $11^{\circ} 42$ mins. (the inlet port extending horizontally) and the angle between successive arms when they are latched together is also $11^{\circ} 42$ mins. It has already been stated that each arm in succession has to be unlatched from the arm above it and moved down into latching position relatively to an arm at the operating station. This movement takes place through an angle of $8^{\circ} 52$ mins. Thus there exists between an arm which is at the operating station and an arm which is above it, and which is to be brought down toward it, an angle of $11^{\circ} 42$ mins. plus $8^{\circ} 52$ mins., which equals an angle of $20^{\circ} 34$ mins. Such an enlarged gap is provided at the operating station to allow a shoe to be assembled conveniently on the arm which is in work-receiving position. It will therefore be understood that the twenty-nine arms which are not connected to the valve casing, except by the air-supply pipes which connect their pads to their bores, travel through an angle of $8^{\circ} 52$ mins. (while the valve casing is stationary) as they move successively into jacking position relatively to an arm which is at the operating station. As before stated, the pipes 214 which connect the pads on the arms to the bores in the valve casing comprise rigid metal tubes connected to nipples in the bores by small flexible portions near the valve casing. Each bore which is connected to a pad on an arm which is not secured to the valve casing is arranged $4^{\circ} 26$ mins. (considered in the direction of rotation of the arms) in front of the arm which carries the pad with which it communicates. Therefore, when the bore for one of the pads comes into alignment with the exhaust port 216 in the valve, that pad will exhaust although the bore is spaced $4^{\circ} 26$ mins. in front of the arm carrying the pad. Now assuming the arm to be one of the twenty-nine arms which are not rigidly secured to the valve casing it will, after it has moved through the $8^{\circ} 52$ mins. into jacking position around the valve casing, which remains at rest, take up a position $4^{\circ} 26$ mins. in front of the bore and therefore below the exhaust port 216. When this arm has been jacked to the one at the operating station, the arms and valve casing will be rotated as a unit through $11^{\circ} 42$ mins. by the rotation of the notched disc 104. This rotation will present the pad on this arm at the operating station slightly below the horizontal, (i. e. a position $4^{\circ} 26$ mins. below the inlet port) so that the bore for this pad, which is now $4^{\circ} 26$ mins. behind the arm and pad, will come into communication with the hor-

izontal inlet port. At some time after each pad has moved away from the operating station but before it reaches its exhausting position, the arm which is secured to the casing will have been brought down from the exhausting position through $8^{\circ} 52$ mins. into jacking position relatively to an arm at the operating station. The valve casing will accordingly be advanced through $8^{\circ} 52$ mins. relatively to the remaining twenty-nine arms and will therefore carry the bore for each arm from its position $4^{\circ} 26$ mins. behind the arm to its previous position of $4^{\circ} 26$ mins. in front of the arm, thus restoring the previous relation between the arms and the bores for the pads on these arms.

During the $8^{\circ} 52$ mins. movement of the arm to which the valve casing 206 is secured, the bore in the valve casing for the pad on the arm at the operating station will be carried forwardly the same distance away from the inlet port. In order to allow the pad on this arm to communicate with the inlet port 194 in spite of this movement, the bore 220 for this pad is provided with a groove 222 which extends upwardly around the valve casing for $8^{\circ} 52$ mins. This arrangement permits the bore for this pad to remain in communication with the inlet port in spite of the movement of the valve casing. The bore 224 for the pad on the arm which is secured to the valve casing is arranged $4^{\circ} 26$ mins. behind the arm carrying the pad and therefore compressed air will be admitted to the pad on this arm when the arm is at the operating station $4^{\circ} 26$ mins. below the horizontal. In order that the pad on the arm which is secured to the valve casing may exhaust before the arm is moved through its $8^{\circ} 52$ mins. movement into jacking position, the shorter limb of the L-shaped exhaust port 216 runs rearwardly around the valve through an angle of $8^{\circ} 52$ mins. Moreover, the limb is so placed on the valve that the bore 224 for the pad on this arm can alone communicate with it, this bore having an offset cut-away portion 226 (see Figure 3) to permit such communication with the shorter limb of the exhaust port.

It is to be understood that, since the sole and shoe are to be cemented together during the action of the machine, the sole and the lasted-over margins of the upper are coated with cement. Preferably also, in order that the pressure of the pad on the shoe bottom may not disturb the bottom filling material which lies on the insole of the shoe between the overlasted margins of the upper, the bottom filling material comprises a layer of relatively firm yet resilient felt, of a thickness approximately equal to that of the upper materials.

The operation of the machine is as follows:— Assuming that one of the pads, not being the pad on the arm to which the valve casing is secured, is at the operating station, the operator places a sole in a central position on the upper surface of the pad. He then trips the treadle 52 to cause the carriages 30, 32 to approach the pad and the sole-engaging feelers to come into contact with the toe and heel end of the sole. The shoe-engaging members at the toe end assume correct positions relatively to the toe end of the sole automatically, and the shoe-engaging members at the heel end take correct positions relatively to the sole when the operator depresses the hand lever 50. The operator then places a shoe on the sole between the shoe-engaging members so that the toe and heel ends of the shoe are correctly positioned relatively to the sole and are

ready for the pressing operation. The operator depresses the treadle 92 which is connected to the weighted lever 76 to swing the latter downwardly and unlatch the arm next above the operating station from the arm above it and to allow the arm to descend until it becomes latched to the arm which is at the operating station. The shoe-engaging members 54 and 56 on the underside of the pad on the upper arm will then engage the shoe on the pad at the operating station. The operator then depresses a treadle 228 which, by means of a rod 230, operates a valve 232 in the valve casing 182 (see Figure 3) to allow compressed air to be supplied both to the inlet port 194 and to the make-up port 196 and, through the inlet valve, to allow compressed air to enter the pad which is at the operating station. This will have the effect of pressing the entire upper surface of the sole firmly against the lasted shoe. He next operates the push lever 128. The first result of the movement of this lever is to cause the clutch 130 to engage to withdraw the carriages 30, 32 from the pad. As the carriages are returned to inoperative positions the weights 53 are raised, a latch 51 on the treadle 52 maintaining the weights in elevated position. When the latch 51 is released, the carriages will be lowered over the next pad, so that a shoe and sole may be positioned on that pad for a sole-pressing operation. After the carriages have been withdrawn to their inoperative positions, the clutch 130 will be thrown out of operation through the co-operation of the notched plate 144 and the cam roll 174. Before this happens, however, the clutch 114, which drives the two notched plates 104 and 120 aforesaid, is thrown into operation through mechanism previously described and the consequent rotation of the larger notched plate 104 causes the arms, which are latched together, to rotate as a unit. This rotation continues until the next highest pad (i. e. the pad on the arm immediately above that which was last at the operating station) is in turn presented at the operating station. When this has occurred the cam roll 124 which runs on the periphery of the smaller notched plate 120 will enter one of the notches in that plate and will cause the lever 126 which carries it to rock so as to throw the driving clutch 114 out of operation. Thus the arms will be brought to rest with another pad at the operating station. A second sole and shoe may then be mounted upon this pad and the operations of correctly positioning the shoe and sole on the pad, of drawing down the next highest arm and latching it to the arm carrying the shoe, of inflating the pad, and of withdrawing the feelers from over the pad and throwing into operation the driving clutch for the arms will be repeated. As each pad which is operating to press a sole against a shoe comes into the position above the operating station, the bore in the valve casing 206 which communicates with that pad comes over the exhaust port 216 on the valve and the pad becomes deflated. Thus, when the treadle 92 is depressed to lower the arm to latch it to the one beneath it, the shoe and the sole which will have been pressed to it are merely resting by their own weight on the deflated pad and may be removed before the pad which is at the operating station is inflated. It is contemplated that such time will be taken by the operator in jacking and unjacking shoes from the pads that, in conjunction with the time required for operation of the driving means, twenty minutes will have elapsed

between jacking and unjacking a single shoe and that during this time the cement between the shoe and sole will have set.

A manually controlled valve 234 is included in each pipe 214 which leads from a bore in the valve casing to a pad and each valve is so arranged that it normally allows direct communication between the bore and the pad. Each valve may, however, be rotated by means of a handle to cut off communication between the bore and the pad and to allow compressed air in the pad to exhaust through the valve into the atmosphere. Such an arrangement will be found of use if it is desired to relieve a shoe from pressure at any time after the pad on which it rests has been inflated, for example, if the shoe and sole should not, for any reason, have been correctly positioned.

Having thus described my invention, what I claim as new and desire to secure by Letters Patent of the United States is:—

1. In a machine for cement attaching soles to shoes, an endless series of pads arranged each to receive a shoe and sole, said pads being mounted in pad boxes which are positioned in close proximity to each other, one over another, so that the bottom of one pad box may be utilized for holding a shoe on the next pad.

2. In a machine for cement attaching soles to shoes, an endless series of pads each mounted in a pad box and arranged to hold a shoe and sole, said pad boxes being positioned one over another in close proximity to each other so that the bottom of an upper pad box may be utilized for clamping a shoe on a lower pad, thereby obtaining a compact arrangement of the series of pad boxes and permitting a large number of boxes to be employed.

3. In a machine for cement attaching soles to shoes, a series of pads mounted in pad boxes and arranged each to receive a shoe and sole, said pads being located in close proximity to each other with the top of one pad facing the bottom of the next pad box so that the bottom of one pad box may be utilized for holding a shoe on the next pad, a greater space being provided between the pads at one point in the series to permit the introduction of a sole and shoe.

4. In a machine for cement attaching soles to shoes, a series of pads each arranged to receive a shoe and sole, the pads of the series being mounted in pad boxes located closely adjacent to each other so that the bottom of one pad box may be utilized to clamp a shoe and sole placed on the next pad, and means for separating one pad from the next box to unclamp a shoe and permit the introduction of another shoe and sole in its place.

5. In a machine for cement attaching soles to shoes, a plurality of pad boxes spaced equidistantly from and in close proximity to each other except at one point, pads mounted in said pad boxes and arranged each to receive a sole and shoe, and means mounted on the bottom of the pad boxes each for holding a sole and shoe on the pad of an adjacent pad box.

6. In a machine for cement attaching soles to shoes, a plurality of pad boxes located in an endless series in close proximity to each other, yieldable pads mounted in said pad boxes and arranged each to receive a sole and shoe, and abutments mounted on the bottoms of the pad boxes each for clamping a shoe and sole on the pad of the next box.

7. In a machine for cement attaching soles to

- shoes, a plurality of pad boxes positioned in an endless series in close proximity to each other, means for moving the series of boxes to present the boxes in turn at an operating station, yielding pads mounted in said pad boxes and arranged each to apply pressure to a sole and shoe, each box being arranged for movement relatively to the other boxes when in the vicinity of the operating station to facilitate access to the pads for the removal and presentation of shoes, and pressure-receiving abutments on the bottom of each pad box arranged to clamp a sole and shoe on the pad of the next pad box when said relative movement is effected. 5 80
14. In a machine for cement attaching soles to shoes, the combination of a series of arms provided with pad boxes, each pad box having a pad arranged to receive a shoe and sole and each arm being positioned in close proximity to another arm except at one point in the series, and clamping means on the bottom of each pad box for holding a shoe and sole on a pad in another pad box. 90
15. In a machine for cement attaching soles to shoes, a plurality of pad boxes provided with pads, each pad being arranged to receive a shoe and sole and the pad boxes being positioned in an endless series sufficiently close to each other except at one point in the series to enable the bottom of one pad box to be utilized for clamping a shoe on the top of the next pad, and means for effecting separation between adjacent pads at said point to unclamp a shoe and permit the introduction of another shoe. 95
16. In a machine for cement attaching soles to shoes, the combination of a plurality of pad boxes each arranged to receive a shoe and sole and positioned for movement in close proximity to each other, and pressure-receiving abutments mounted on the bottom of each pad box and constructed and arranged to engage the cone of a last in a shoe and the toe portion of said shoe respectively 100 while the shoe is resting on an adjacent pad box, said abutments being pivotally adjustable relatively to each other to accommodate various sizes and shapes of lasts. 105
17. In a machine for cement attaching soles to shoes, the combination of a plurality of inflatable pads mounted in pad boxes, said pads being arranged each to receive a shoe and sole and said pad boxes being positioned to rotate in close proximity to each other about a fixed axis, adjustable pressure-receiving abutments mounted on the bottom of each pad box for engaging the cone of a last in a lasted shoe and the toe portion of said shoe respectively while the shoe is resting on the pad of an adjacent box, means for 110 securing each pad box to the next adjacent pad box, and means for inflating the pads to apply pressure to the respective shoes and soles mounted thereon. 115
18. In a machine for cement sole attaching, the combination of a plurality of pad boxes each having a pad constructed and arranged to receive a shoe and sole and mounted to rotate in close proximity to each other about a horizontal axis, adjustable pressure-receiving means mounted on the bottom of each pad box and arranged to clamp a shoe on the upper surface of the pad of an adjacent pad box, and means for rotating each pad box in turn relatively to the other pad boxes to bring the rotated pad box into shoe-clamping position relatively to the next pad box. 125 130
19. In a machine for cement sole attaching, the combination of a plurality of pad boxes each arranged to receive a shoe and sole and mounted to rotate in close proximity to each other about a fixed horizontal axis, a space being provided between adjacent boxes at one point in the path of rotation, clamping means on the bottom of each pad box constructed and arranged to engage the cone of a last in a shoe and the toe portion of said 140 shoe respectively while the shoe is resting on the next pad box, and treadle-operated means for rotating a pad box about the horizontal axis to bring said pad box into shoe-clamping position relatively to a shoe on the next pad box. 145 150
20. In a machine for cement attaching soles to shoes, the combination of an endless series of pad boxes arranged each to receive a shoe and sole 25

19. In a machine for cement sole attaching, the combination of a horizontal shaft, a series of pad boxes having pads adapted to receive a shoe and sole, said pad boxes being arranged to rotate in close proximity to each other about the horizontal shaft, clamping means on the bottom of each pad box constructed and arranged to engage the cone of a last in a shoe and the toe portion of said shoe respectively while the shoe is resting on an adjacent pad, treadle-operated means for rotating one pad box about the horizontal shaft to bring said pad box into shoe-clamping position relatively to a shoe on an adjacent pad, and latches for securing said pad box in shoe-clamping position. 80 85
20. In a machine for cement sole attaching, the combination of a plurality of closely adjacent pad boxes each carrying an inflatable pad constructed and arranged to apply pressure to a shoe and sole, said pad boxes being mounted for progression in an endless series, a space being provided between the boxes at one point in the series to permit the introduction of a shoe and sole, pressure-receiving abutments mounted on the bottom of each pad box and arranged to clamp a shoe on the next pad box by relative movement of the boxes toward each other through said space, means for effecting progression of the series to present successive pad boxes at an operating station, and means for admitting fluid under pressure to the pads to apply pressure to shoes and soles mounted respectively on the successive pads. 90 95
21. In a machine for cement sole attaching, the combination of a plurality of adjacent pad boxes each having a dilatable pad constructed and arranged to receive a shoe and sole, said boxes being mounted to move in an endless path and being positioned with their longest axes parallel to each other and perpendicular to their path of movement, pressure-receiving abutments at the bottom of each pad box for engaging a shoe mounted on the next pad, means for effecting progression of the boxes along said path to present the boxes in turn at an operating station, mechanism arranged to permit a pad box adjacent to the operating station to be separated from the next pad box to permit the introduction of a shoe and sole on the pad of said pad box, and means for dilating said pad to apply pressure to the shoe and sole mounted thereon. 100 105
22. In a machine for cement sole attaching, the combination of a plurality of closely adjacent pad boxes arranged each to receive a shoe and sole and mounted to rotate in an endless series about a fixed axis, said pad boxes being positioned with their longest axes parallel to each other and perpendicular to the plane of rotation, clamping abutments on the bottom of each pad box for engaging a shoe mounted on an adjacent pad box, and means for effecting progressive rotation of the series about the fixed axis to present the boxes in turn at an operating station, said pad boxes being mounted so that a space will be provided between adjacent boxes at one point in the series to permit the removal of a shoe and the introduction of another shoe. 110 115 120
23. In a machine for cement attaching soles to shoes, the combination of a plurality of closely adjacent pad boxes arranged each to receive a shoe and sole and mounted to rotate in a vertical plane about a fixed horizontal axis, said boxes being positioned in an endless series with their longitudinal axes parallel to each other and at right angles to the plane of rotation, clamping 125 130 135 140 145
- means on the bottom of each box for clamping a shoe on the next box, means for securing each pad box to the next pad box, power-operated means for effecting progressive rotation of the series about said axis to present the boxes successively at an operating station, and treadle-operated means for releasing a pad box adjacent to the operating station from the next box and for moving it into clamping relation to a shoe on another pad box. 150
24. In a machine for cement attaching soles to shoes, the combination of a plurality of closely adjacent pad boxes each provided with a pad constructed and arranged to receive a shoe and sole, said pad boxes being arranged to rotate in an endless series about a fixed horizontal axis, a pressure-receiving abutment mounted on the bottom of each pad box and arranged to clamp a shoe on the next pad as each pad box is rotated about the horizontal axis toward an adjacent pad, and means for locking each pad box in shoe-clamping position relatively to an adjacent pad. 155
25. In a cement sole attaching machine, the combination of a shaft, a plurality of arms mounted for rotation about said shaft, said arms being positioned closely adjacent to each other except at one point and each arm carrying at its outer extremity a shoe and sole receiving and clamping unit, and means for effecting separation between the arms at said point to provide a space for the removal of a shoe and the introduction of another shoe. 160 165
26. In a cement sole attaching machine, the combination of a shaft, a plurality of closely adjacent arms mounted for rotation in an endless series about said shaft, each arm carrying at its outer extremity a shoe and sole receiving and clamping unit, said units being arranged one above another with their longest axes parallel to each other so that the bottom of one unit may be utilized for clamping a shoe against the top of another, and means for effecting progression of the series to present the units in turn at an operating station. 170 175
27. In a cement sole attaching machine, the combination of a horizontal shaft, a plurality of closely adjacent arms radially mounted on said shaft and arranged to rotate in a vertical plane, pad boxes being secured to said arms constructed and arranged each to receive a shoe and sole, a pressure-receiving abutment on the bottom of each pad box for clamping a shoe on an adjacent pad box, and means for locking each arm to the next arm. 180 185 190
28. In a cement sole attaching machine, the combination of a horizontal shaft, a plurality of adjacent arms radially mounted on the shaft and arranged to rotate in a vertical plane about said shaft, pad boxes being secured to the outer extremities of the arms constructed and arranged each to receive a shoe and sole, said pad boxes having their longest axes parallel to each other and perpendicular to the length of the arms, a pressure-receiving abutment on the bottom of each pad box for clamping a shoe on the next pad box, means on the arms for latching each arm to the next arm, means for moving each arm successively into shoe clamping position relatively to the next arm, and means for moving the arms as a unit to present each arm which is in shoe clamping position at an operating station. 195
29. In a cement sole attaching machine, the combination of a stationary horizontal shaft, a 200

- plurality of closely adjacent arms radially mounted on the shaft and arranged to rotate in a vertical plane about said shaft, pad boxes on said arms each constructed and arranged to receive a shoe and sole, relatively adjustable abutments on the bottom of each pad box for clamping a shoe on an adjacent pad box, means for locking each arm to an adjacent arm, and means for unlocking each arm from said adjacent arm.

5 30. In a cement sole attaching machine, the combination of a stationary horizontal shaft, a plurality of closely adjacent arms radially mounted on the shaft and arranged to rotate in a vertical plane about said shaft, pad boxes mounted on the outer extremities of the arms and arranged each to receive a shoe and sole, said pad boxes having their longest axes parallel to each other and perpendicular to the length of the arms, abutments on the bottom of each pad box for engaging and holding a shoe on an adjacent arm, latches on the arms for securing each arm to the next arm, treadle-operated means for releasing one arm from the next arm, and means for moving said arm into shoe-engaging position relatively to another arm.

10 31. In a cement sole attaching machine, the combination of a horizontal shaft, a plurality of closely adjacent arms radially mounted on the shaft and arranged to rotate in a vertical plane, pad boxes secured to the other extremities of the arms and having pads constructed and arranged each to receive a shoe and sole, said pad boxes having their longest axes parallel to each other and perpendicular to the length of the arms, adjustable pressure-receiving abutments on the bottom of each pad box for clamping a shoe on the pad of an adjacent pad box, latches on the arms for securing each arm to an adjacent arm, and means for effecting progressive rotation of the interconnected arms about the horizontal shaft to present the arms successively at an operating station.

15 32. In a cement sole attaching machine, the combination of a stationary horizontal shaft, a plurality of closely adjacent arms radially mounted on the shaft and arranged to rotate in a vertical plane about said shaft, pad boxes secured to the outer extremities of the arms each having an inflatable pad constructed and arranged to apply pressure to a shoe and sole mounted on said pad, said pad boxes having their longest axes parallel to each other and perpendicular to the length of the arms, a pressure-receiving abutment on the bottom of each pad box for clamping a shoe on an adjacent pad, latches on the arms for securing each arm to an adjacent arm, pins on the arms cooperating with the latches to connect the arms, and power-operated means for effecting progressive rotation of the interconnected arms step by step about the horizontal shaft to present the pad boxes successively at an operating station.

20 33. In a cement sole attaching machine, the combination of a stationary horizontal shaft, a plurality of closely adjacent arms radially mounted on the shaft and arranged to rotate in a vertical plane about said shaft, pad boxes secured to the outer extremities of the arms and arranged to receive a shoe and sole, said pad boxes having their longest axes parallel to each other and perpendicular to the length of the arms, abutments on the bottom of each pad box for clamping a shoe on an adjacent pad box, latches on the arms for connecting each arm to an adjacent arm, pins on the arms cooperating with said latches

25 to connect the arms, treadle-operated mechanism for actuating the latches to release one arm from an adjacent arm, means for lowering the released arm into shoe-clamping position relatively to an adjacent arm, and power-operated means for effecting progressive rotation of the interconnected arms step by step about the horizontal shaft to present the arms successively at an operating station.

30 34. In a machine for cement attaching soles to shoes, a plurality of inflatable pads each constructed and arranged to receive a shoe and sole, said pads being mounted in a series of pad boxes located on arms arranged in close proximity to each other except at one point in the series, means on the bottom of each pad box for holding the shoe on the pad in the pad box next in the series, and means for inflating each pad separately to apply pressure to the shoe and sole mounted thereon, said means operating automatically after its initial actuation to hold a shoe on one pad pressed against the holding means on the bottom of the next pad.

35 35. In a machine for cement attaching soles to shoes, a plurality of hollow pads each constructed and arranged to receive a shoe and sole, said pads being mounted in an endless series in pad boxes positioned in close proximity to each other except at one point in the series so that clamping means on the bottom of each pad box may be utilized for clamping a shoe and sole on the top of the next pad, and means for admitting fluid under pressure into each pad in turn to apply pressure to the shoe and sole mounted thereon, said means being actuated initially by a treadle and thereafter operating automatically to hold a shoe on one pad pressed against the holding means on the bottom of the next pad.

40 36. In a machine for cement sole attaching, a series of hollow pads mounted in pad boxes, each pad being constructed and arranged to receive a shoe and sole and the pad boxes being arranged in close proximity to each other except at one point in the series so that the bottom of one pad box may be utilized for clamping a shoe on the top of an adjacent pad, means for effecting separation between the pad boxes at said point to provide a space for the introduction of a shoe and sole, and means for admitting fluid under pressure into each pad to apply pressure to a shoe and sole mounted on said pad.

45 37. In a machine for cement attaching soles to shoes, a plurality of dilatable pads each constructed and arranged to receive a shoe and sole, said pads being mounted in close proximity to each other on the outer extremities of a corresponding number of arms so that the bottom of each arm may be utilized for clamping a shoe on the top of an adjacent pad, means for dilating each pad in turn to apply pressure to a shoe and sole mounted thereon, and means for periodically restoring the pressure in any pad in which leakage has occurred, thereby maintaining a substantially uniform pressure on the shoe until the sole-attaching cement has set.

50 38. A machine for cement attaching soles to shoes having, in combination, a series of hollow pads each constructed and arranged to receive a shoe and sole, said pads being located on arms positioned in close proximity to each other so that the bottom of each arm may be utilized as a pressure receiving element for clamping a shoe on the top of an adjacent pad, and being mounted to provide a space at one point in the series for the introduction of a shoe and sole, means for

admitting fluid to the pads to apply pressure to the shoes and soles, and means for replenishing the fluid in the pads to keep this pressure substantially uniform while the sole-attaching cement is setting.

39. A machine for cement attaching soles to shoes having, in combination, an endless series of pads arranged each to receive a shoe and sole, means for clamping the shoe and sole on each 10 pad, means for effecting progression of the series to present each pad in turn at an operating station, and means for relatively locating the shoe and sole with respect to each other.

40. A machine for cement attaching soles to 15 shoes having, in combination, an endless series of pads arranged each to receive a shoe and sole, means for clamping the shoe and sole on each pad, means for effecting progression of the series to present each pad in turn at an operating station, and means permanently located at the operating 20 station for relatively locating the shoe and sole with respect to each other as each pad is presented in turn at the operating station.

41. A machine for cement attaching soles to 25 shoes having, in combination, an endless series of pads arranged each to receive a shoe and sole, means for clamping the shoe and sole on each pad, means for effecting progression of the series to present each pad in turn at an operating station, and means movable into and out of position 30 over the pad for relatively locating the shoe and sole with respect to each other.

42. A machine for cement attaching soles to 35 shoes having, in combination, an endless series of pads arranged each to receive a shoe and sole, means for clamping the shoe and sole on each pad, means for effecting progression of the series to present each pad in turn at an operating station, and means movable into and out of position 40 over a pad at the operating station for relatively locating the shoe and sole with respect to each other as each pad is presented in turn at said operating station.

43. A machine for cement attaching soles to 45 shoes having, in combination, an endless series of pads arranged each to receive a shoe and sole, pad boxes for holding the pads, abutments on the bottom of each pad box for clamping a shoe and sole on the pad of an adjacent pad box, and means movable into and out of position over the 50 pads for relatively locating the shoes and soles mounted thereon.

44. A machine for cement attaching soles to 55 shoes having, in combination, an endless series of pads mounted in pad boxes and arranged each to receive a shoe and sole, said pad boxes being positioned in close proximity to each other so that the bottom of one pad box may be utilized for clamping a shoe and sole on an adjacent box, means for effecting progression of the series to 60 present each pad box in turn at an operating station, and means movable into and out of position over the pad at the operating station for locating the shoe and sole relatively to each other.

45. A machine for cement attaching soles to 65 shoes having, in combination, an endless series of pad boxes provided with pads each arranged to receive and apply pressure to a shoe and sole, said pad boxes being located in close proximity to each other except at one point in the series where 70 a space is provided to facilitate the introduction of a shoe and sole, means for clamping a shoe and sole on the pad of each pad box, means for effecting progression of the series to present each pad in turn at an operating station, and means 75

movable into and out of position over each pad for relatively locating the shoe and sole mounted thereon.

46. A machine for cement attaching soles to 80 shoes having, in combination, a plurality of arms provided with hollow pads, each pad being constructed and arranged to receive a shoe and sole and the arms being arranged in an endless series in close proximity to each other except at one point in the series so that the bottom of one arm may be utilized for clamping a shoe on the pad of another arm, means for effecting progression of the arms to present each pad at a work-receiving station, and means for admitting fluid under pressure to each pad in turn at the work-receiving station to apply pressure to a shoe and sole mounted thereon.

47. A machine for cement attaching soles to 85 shoes having, in combination, a plurality of hollow pads each arranged to receive a shoe and sole and each being held at the outer extremity of a radially mounted arm, said arms being movable relatively to each other and being positioned in close proximity to each other in an endless series 90 so that the bottom of each arm may be utilized for clamping a shoe on the top of the next adjacent pad, means for effecting progression of the series step by step to present each pad in turn at a work-receiving station, means for admitting fluid under pressure into each pad at the work-receiving station to apply pressure to a shoe and sole mounted thereon, and means for maintaining substantially a predetermined pressure in the 95 pads while the sole attaching cement is setting.

48. In a machine for cement sole attaching, 100 a plurality of hollow pads each constructed and arranged to apply pressure to a shoe and sole, said pads being mounted in pad boxes on the ends of arms which are arranged in an endless series closely adjacent to each other except at one 105 point so that pressure-receiving abutments on the bottom of each pad box may be utilized to clamp a shoe on the top of the pad of an adjacent arm, means for effecting progression of the series of arms step by step to present each pad in turn at 110 an operating station, means for supplying fluid under pressure to the pads at the operating station, and means for automatically maintaining the pressure in the pads during progression of the series.

49. A machine for cement attaching soles to 115 shoes having, in combination, a plurality of pads each constructed and arranged to apply pressure to a shoe and sole, said pads being mounted on arms which are arranged in an endless series 120 closely adjacent to each other except at one point so that the bottom of each arm may be utilized for clamping a shoe on an adjacent arm, means for effecting progression of the series of arms step by step to present each arm in turn at a 125 work-receiving station, operator controlled means for supplying fluid under pressure to the pads of said arms successively at the work-receiving station, and means acting simultaneously with said fluid supplying means for restoring the pressure in other pads of the series in which the pressure has fallen because of leakage during progression of said series.

50. A machine for cement attaching soles to 130 shoes having, in combination, a plurality of hollow pads each constructed and arranged to apply pressure to a shoe and sole, said pads being mounted on arms which are arranged in an endless series closely adjacent to each other except at 135 one point in the series so that abutments on the 140

145 150

- bottom of each arm may be utilized for clamping a shoe on the top of the pad on an adjacent arm, means for effecting progression of the arms step by step to present each pad in turn at an operating station, means for supplying each pad with compressed air at said operating station to cause pressure to be applied to a shoe clamped on said pad, means for exhausting the air from the pad at an air exhausting station, and means whereby the pads are periodically restored to their initial pressure after leaving the operating station and before reaching the air exhausting station. 51. A machine for cement attaching soles to shoes having, in combination, a series of hollow pads each constructed and arranged to apply pressure to a shoe and sole, said pads being mounted in pad boxes which are arranged closely adjacent to each other except at one point in the series so that the bottom of each pad box may be utilized for clamping a shoe on the top of a pad in an adjacent pad box, means for effecting progression of the series step by step to present each pad in turn at a work-receiving station, means for supplying compressed air to each pad at the work-receiving station, and means for automatically restoring the compressed air in any of the pads in which loss of air may occur after leaving the work-receiving station. 52. A machine for cement attaching soles to shoes having, in combination, a plurality of hollow pads each arranged to receive a shoe and sole on its upper surface, said pads being mounted one over another in an endless series and being positioned in close proximity to each other except at one point in the series, pressure-receiving abutments under each pad for clamping a shoe and sole on the upper surface of an adjacent pad, means for moving one pad from its position adjacent to another pad to unclamp a shoe and permit the introduction of another shoe, and manually-controlled means for admitting fluid under pressure to each pad to apply pressure to the shoe and sole clamped on its upper surface. 53. A machine for cement attaching soles to shoes having, in combination, a plurality of hollow pads for applying pressure to a shoe and sole, said pads being mounted in pad boxes arranged one over another in close proximity except at one point so that the bottom of an upper pad box may be utilized to clamp a shoe on a lower pad, means for effecting separation of a lower pad box from an upper pad box to permit the removal of a shoe and the introduction of another shoe on the lower pad, manually-controlled means for admitting fluid under pressure to the lower pad to apply pressure to the shoe, and means for automatically exhausting the fluid from the lower pad. 54. A machine for cement attaching soles to shoes having, in combination, a plurality of hollow pads for applying pressure to shoes and soles, said pads being mounted in pad boxes arranged in an endless series sufficiently close to each other except at one point in the series to enable the bottom of each box to be utilized for clamping a shoe on the top of an adjacent pad, means at said point in the series for effecting separation between adjacent pads to unclamp a shoe and permit the introduction of another shoe, manually-controlled means for admitting fluid under pressure into the pads to apply pressure to the respective shoes mounted thereon, and automatic means for periodically restoring the pads to a predetermined pressure while the sole-attaching cement is setting. 55. A machine for cement attaching soles to shoes having, in combination, a plurality of inflatable pads for applying pressure to shoes and soles, said pads being supported on arms arranged sufficiently close to each other except at one point to enable the bottom of one arm to be utilized for clamping a shoe on the top of the pad of another arm, means for effecting progression of the arms to present the pads in turn at a work-receiving station, means for applying fluid pressure to each pad at the work-receiving station, means for periodically restoring the pressure in said pads after they have progressed beyond the work-receiving station, thereby maintaining substantially the required pressure in each pad during its progression to an exhaust position, and means for automatically exhausting the fluid from the pads as they reach said exhaust position. 56. A machine for cement attaching soles to shoes having, in combination, a plurality of pad boxes having hollow dilatable pads mounted therein and arranged each to receive a shoe and sole, means for automatically connecting each pad box to an adjacent pad box, treadle-operated means for disconnecting one pad box from an adjacent pad box to provide a space for the removal of a shoe and the introduction of a shoe and sole on the pad in the first-mentioned pad box, and means for admitting fluid under pressure to said pad to apply pressure to the shoe and sole mounted thereon. 57. A machine for cement attaching soles to shoes having, in combination, a plurality of inflatable pads arranged each to receive a shoe and sole and mounted in an endless series with their longest axes parallel to each other and perpendicular to a vertical plane, means for effecting progression of the series to present the pads in turn at an operating station, treadle-operated mechanism for effecting separation between two of the pads to provide a space for the removal of a shoe and the introduction of another shoe, means for supplying fluid under pressure to inflate the pads, and means for automatically exhausting the fluid to deflate the pads. 58. A machine for cement attaching soles to shoes having, in combination, a plurality of closely adjacent pad boxes, hollow pads mounted in said pad boxes and constructed and arranged each to receive a shoe and sole, said pad boxes being located in an endless series with their longest axes parallel to each other, pressure-receiving abutments on the bottom of each pad box constructed to engage a shoe on the next pad, means for securing each pad box to the next pad box, means for effecting progression of the series to present each pad in turn at a shoe receiving station, means for releasing a pad box at the receiving station from the next pad box to permit the removal of a shoe and the introduction of another shoe, means for admitting fluid under pressure into a pad at the receiving station to apply pressure to a shoe thereon, and means for subsequently exhausting the fluid to permit the removal of said shoe. 59. A machine for cement attaching soles to shoes having, in combination, a plurality of adjacent pad boxes, yielding pads mounted in said boxes and arranged each to receive a shoe and sole, said boxes being positioned in an endless series, clamping means on the bottom of each pad box for holding a shoe on an adjacent pad, means for engaging each pad box with an adjacent pad box, means for effecting stepwise progression of the series of boxes to present the pads.

successively at an operating station, there being at that station a space between adjacent boxes, and means for releasing the pad box at one side of the space from an adjacent box and moving it through said space into proximity to the box at the other side of said space, thus providing for the removal of the shoe from the pad of the released box and the introduction of another shoe thereon, said releasing means being again operable to release the pad box at the other side of the space and to cause it to be engaged with the box on the pad of which the shoe has been placed.

60. A machine for cement attaching soles to shoes having, in combination, a plurality of closely adjacent pad boxes, hollow pads mounted in said boxes and arranged each to receive a shoe and sole, said boxes being positioned in an endless series with their longest axes parallel to each other, clamping abutments on the bottom of each pad box for clamping a shoe on an adjacent pad, means for latching each pad box to an adjacent box, means for effecting progression of the series to present each pad in turn at an operating station, there being at that station a space between adjacent boxes, means for unlatching the pad box at one side of said space from the adjacent box and moving it through said space into shoe clamping engagement with the box at the other side of said space, thus providing for the removal of the shoe from the pad of the unlatched box and the introduction of another shoe thereon, said unlatching means being again operable to unlatch the pad box at the other side of the space and to move it into shoe clamping engagement with the box on the pad of which the shoe has been placed, and means for admitting fluid under pressure into said pad to apply pressure to the shoe.

61. A machine for cement attaching soles to shoes having, in combination, a plurality of closely adjacent pad boxes arranged for progression in an endless series, yielding pads mounted in said boxes and adapted each to receive a shoe and sole, pressure-receiving abutments on the bottom of each pad box for clamping a shoe and sole, said abutments being adapted to engage a shoe on the pad of an adjacent pad box, means for effecting progression of the series to present the pads in turn at an operating station, the pad boxes being constructed and arranged to provide a space between them at said operating station, and means for moving the pad box at one side of said space to bring the pressure-receiving abutments on that box into shoe clamping relation with a shoe on the pad of the pad box at the other side of said space.

62. A machine for cement attaching soles to shoes having, in combination, a plurality of closely adjacent pad boxes arranged to rotate in an endless series about a fixed axis, yielding pads mounted in said boxes and adapted each to receive a shoe and sole, pressure-receiving abutments on the bottom of each pad box adapted to engage and clamp a shoe on an adjacent pad, means for rotating the series about said axis to present the pads in turn at an operating station, the pads being mounted to provide a space between them at the operating station, and means for rotating the pad box at one side of said space about said axis to bring the pressure-receiving abutments on that box into shoe clamping position relatively to a shoe on the pad of the pad box at the other side of said space.

63. A machine for cement attaching soles to shoes having, in combination, a plurality of closely adjacent pad boxes arranged to rotate in an endless series about a fixed axis, flexible hollow pads mounted in said boxes and arranged each to receive a shoe and sole, abutments on each pad box for clamping a shoe and sole mounted on an adjacent pad box, means for rotating the series about said axis to present the pads in turn at an operating station, the pad boxes being constructed and arranged to provide a space between them at the operating station, means for rotating the pad box at one side of said space about said axis to bring the abutments on that box into shoe clamping position relatively to a shoe on the pad of the pad box at the other side of said space, and means for admitting fluid under pressure to said pad to apply pressure to the shoe mounted thereon.

64. A machine for cement attaching soles to shoes having, in combination, a plurality of pad boxes arranged to rotate in an endless series about a fixed axis, said pad boxes being positioned closely adjacent to each other except at one point in the series, flexible hollow pads mounted in the pad boxes and arranged each to receive a shoe and sole, clamping means mounted on the bottom of each pad box and adapted to engage a shoe on the pad of an adjacent pad box, means for rotating the series about said axis to present the pads successively at an operating station, means for rotating each pad box about said axis to bring the clamping means on that box into shoe-clamping position relatively to the pad box at the operating station, means for admitting fluid under pressure to the pad at the operating station to apply pressure to a shoe mounted thereon, and means for keeping the pressure on the shoe substantially uniform.

65. A cement sole attaching machine having, in combination, a stationary horizontal shaft, a plurality of closely adjacent arms radially mounted on the shaft and arranged to rotate in a vertical plane about said shaft, pad boxes secured to the outer extremities of the arms, said pad boxes having their longest axes parallel to each other and perpendicular to the length of the arms so that each box will be presented side on at an operating station, hollow pads mounted in the pad boxes and having a portion of their upper surfaces exposed to receive a shoe and sole, said pads being composed of dilatable material capable of expanding under pressure, abutments on the bottom of each pad box for clamping a shoe and sole mounted on the exposed surface of an adjacent pad, and means for expanding said pads.

66. A cement sole attaching machine having, in combination, a stationary horizontal shaft, a plurality of closely adjacent arms radially mounted on the shaft and arranged to rotate in a vertical plane about said shaft, pad boxes secured to the outer extremities of the arms and having their longitudinal axes parallel to each other and to the horizontal shaft so that each box will be presented side on relatively to an operating station, hollow pads confined in the pad boxes and having a portion of their upper surfaces exposed to receive a shoe and sole, said pads being composed of dilatable material capable of expanding under pressure, and means for dilating said pads to cause pressure to be applied to the respective

- soles and shoes mounted on the exposed surfaces of the pads.
67. A cement sole attaching machine having, in combination, a stationary horizontal shaft, a plurality of closely adjacent arms radially mounted on the shaft and arranged to rotate in a step-wise manner about said shaft, means for effecting rotation of the arms about the horizontal shaft, pad boxes secured to the outer extremities of the arms and arranged with their longest axes parallel to each other, pressure-receiving abutments on the bottom of each pad box for clamping a shoe on an adjacent pad box, dilatable pads confined in said pad boxes, each pad having a portion of its upper surface exposed to receive a shoe and sole, said pads being composed of yieldable material capable of expanding under pressure, and means including a manually-controlled valve for supplying fluid under pressure to each pad in turn to cause said pads to apply pressure to respective soles and shoes mounted on the exposed surfaces thereof. 80
68. A cement sole attaching machine having, in combination, a stationary horizontal shaft, a series of pad boxes adapted to rotate about said shaft, said pad boxes being interconnected except at one point in the series, a plurality of dilatable pads mounted in the pad boxes and having exposed upper surfaces arranged each to receive a shoe and sole, means for rotating the series about said shaft to present the pads successively at an operating station, means for supplying fluid under pressure to each pad after it is presented at said operating station, said pads being constructed and arranged to provide a space at the operating station for the removal of a shoe and the introduction of another shoe on each successive pad, means for moving a pad through said space toward an adjacent pad, and means for automatically exhausting the fluid from the pad prior to its movement toward said adjacent pad. 90
69. A machine for cement attaching soles to shoes having, in combination, a series of pad boxes provided with inflatable pads each arranged to apply pressure to a shoe and sole mounted thereon, means on the bottom of each pad box for clamping the shoe and sole on an adjacent pad, means for effecting progression of the series to present each pad in turn at an operating station, means for inflating the pads to cause pressure to be applied to the respective shoes and soles clamped thereon, said means operating automatically after its initial actuation, and means for periodically reinflating the pads during progression of the series to make up pressure lost from any of the pads through leakage during said progression. 100
70. A machine for cement attaching soles to shoes having, in combination, a plurality of inflatable pads mounted in pad boxes, each pad being arranged to receive and apply pressure to a shoe and sole, means on each pad box for clamping a shoe and sole on an adjacent pad, means for admitting fluid under pressure to each pad in turn to cause said pad to apply pressure to the shoe and sole clamped thereon, said means operating automatically after it has been set in operation, means for effecting progression of the pads in an endless series to allow the sole-attaching cement to set while under pressure, and means for periodically restoring the pressure in any of the pads from which fluid has leaked during such progression, said means acting automatically to replenish the fluid in said pads. 110
71. A machine for cement attaching soles to shoes having, in combination, a plurality of pad boxes provided with inflatable pads, each pad being arranged to receive and apply pressure to a shoe and sole, means on the bottom of each pad box for clamping a shoe and sole on an adjacent pad, treadle operated means for inflating each pad in turn to cause a predetermined pressure to be applied to the shoe and sole clamped thereon, said means operating automatically to inflate the pads after one depression of the treadle, means for effecting progression of the inflated pads in an endless series to allow the sole-attaching cement to set while under pressure, and means for periodically restoring the pressure in those pads of the series from which leakage has occurred during said progression, said means acting automatically to reinflate the pads to their original pressure. 120
72. A machine for cement attaching soles to shoes having, in combination, a plurality of hollow pads mounted in pad boxes, each pad being arranged to support and apply pressure to a shoe and sole mounted thereon, means on the bottom of each pad box for securing a shoe and sole on an adjacent pad, means operated initially by a treadle for admitting fluid under pressure to each pad in turn to cause the pads to apply predetermined pressure to the respective shoes and soles mounted thereon, said means acting automatically on the pads after its initial operation, means for effecting progression of each pad after fluid has been admitted thereto to allow the sole-attaching cement to set while under pressure, and means for maintaining said pressure during such progression, said means acting automatically to restore the fluid at definite intervals to any of the pads from which leakage has occurred during said progression. 130
73. A machine for cement attaching soles to shoes having, in combination, a series of inflatable pads mounted in pad boxes and arranged each to support and apply pressure to a shoe and sole mounted thereon, means on the bottom of each pad box for securing a shoe and sole on the pad of another pad box, means for inflating each pad in turn at an operating station to cause predetermined pressure to be applied to the shoe and sole secured thereon, said means being set in operation by a treadle and thereafter operating automatically, means for effecting progression of the inflated pads step by step from the operating station to a pressure-exhausting station, thereby allowing the sole-attaching cement to set while pressure is being applied to the shoes, and means for periodically restoring the original pressure to any pads of the series the pressure of which may have diminished through leakage, said means acting automatically to reinflate said pads at definite intervals during their progression to the pressure-exhausting station. 140
74. A machine for cement attaching soles to shoes having, in combination, a stationary horizontal shaft, a plurality of pad boxes located closely adjacent to each other except at one position and arranged to rotate about said shaft, each of said pad boxes being provided with clamping means on its bottom surface for engaging a shoe, inflatable pads mounted in said pad boxes, each having an upper surface exposed to receive a shoe and sole, said pads being constructed and arranged to be inflated by fluid under pressure so as to apply pressure to shoes and soles mounted respectively thereon, manually-operated means for admitting fluid under pressure to said pads, and means for maintaining said fluid at a sub- 150

stantially uniform pressure while the sole-attaching cement is setting.

75. A machine for cement attaching soles to shoes having, in combination, a stationary horizontal shaft, a plurality of pad boxes mounted for rotation in close proximity to each other about said shaft, each of said pad boxes being positioned parallel to the shaft and having on its bottom surface clamping means for engaging a shoe, dilatable hollow pads mounted in said pad boxes each having an upper surface exposed to receive a shoe and sole, said pads being constructed and arranged to be inflated by compressed air to apply pressure to the respective shoes and soles mounted

10 15 thereon, means for rotating the pads step by step in a body about the horizontal shaft to move each pad in turn from a shoe-receiving station to an air-exhausting station, means for supplying compressed air to the pads at the shoe-receiving 20 25 station, and means for maintaining the compressed air in each pad at substantially the required pressure irrespective of leakage until said pad is presented at the air-exhausting station.

76. A machine for cement attaching soles to 25 shoes having, in combination, a stationary horizontal shaft, a plurality of pad boxes adapted to rotate in an endless series about said shaft, said pad boxes being provided on their bottom surfaces with pressure-receiving abutments for engaging 30 35 a shoe, dilatable hollow pads mounted in said pad boxes each pad being constructed and arranged to apply pressure to a shoe and sole mounted thereon, means for rotating the series step by step about the horizontal shaft to present each pad 40 45 box in turn at an operating station, manually-controlled means for admitting fluid under pressure to each pad to cause pressure to be applied to the respective shoes and soles, means for periodically replenishing the fluid in any of the pads from which fluid has leaked, thereby maintaining a substantially uniform pressure in the pads, and means for automatically exhausting the fluid from each pad before it is presented at the operating station.

45 50 55 60 65 70 75 78. A machine for cement attaching soles to shoes having, in combination, a fixed horizontal shaft, a series of hollow pads each constructed and arranged to apply pressure to a shoe and sole, said pads being mounted in pad boxes which are arranged for rotation about said shaft and positioned closely adjacent to each other except at one point so that each pad box may be utilized for clamping a shoe on the top of an adjacent pad, means for effecting progression of the pad boxes step by step around the shaft to present each pad in turn at an operating station, means for supplying fluid under pressure to each pad presented at said operating station, and means for automatically replenishing the fluid in the pads, said means being constructed and arranged to permit communication of the pads with the fluid supplying means during the greater part of the rotation of the pad boxes about the horizontal shaft.

78. A machine for cement attaching soles to shoes having, in combination, a plurality of pads each arranged to receive a sole and shoe and mounted for progression in an endless series, means for clamping a sole and shoe on each pad, means for effecting progression of the series to present each pad in turn at an operating station, means movable into and out of operative position for locating a sole and shoe on a pad at the operating station, and means for moving the lo-

cating means out of operative position to permit progression of the series.

79. A machine for cement attaching soles to shoes having, in combination, a plurality of pads each arranged to receive a sole and shoe and mounted for progression in an endless series, means movable into and out of position over a pad at an operating station for engaging a sole and shoe and positioning them relatively to each other on said pad, means for clamping the sole and shoe on said pad, means for effecting progression of the series to present the other pads of the series in turn at said operating station, and means for withdrawing the positioning means from engagement with the sole and shoe to permit progression of the series.

80 85 90 95 100 105 80. A machine for cement attaching soles to shoes having, in combination, a plurality of pads each arranged to receive a sole and shoe, said pads being mounted for progression in an endless series, means for engaging a sole and shoe placed on a pad at an operating station to position them relatively to each other on said pad, means for clamping the sole and shoe on said pad, means for effecting progression of the series step by step to present the other pads in turn at said operating station, and means acting automatically to withdraw the positioning means from engagement with the sole and shoe before progressive movement of the series is effected.

110 115 120 125 130 135 81. A machine for cement attaching soles to shoes having, in combination, a plurality of pads each arranged to receive a sole and shoe, said pads being mounted for progression in an endless series past an operating station and being positioned closely adjacent to each other except at the operating station where a space is provided to permit the introduction of a sole and shoe, gages movable into and out of position over a pad at the operating station for relatively positioning a sole and its shoe placed on said pad, means for clamping the sole and shoe on said pad, driving mechanism for effecting progression of the series step by step to present the other pads of the series in turn at said operating station, and means for withdrawing the positioning gages from over the pad at the operating station prior to each step of the progressive movement of the series.

140 145 150 155 160 165 82. A machine for cement attaching soles to shoes having, in combination, a plurality of pads each constructed and arranged to receive a sole and shoe and mounted for progression in an endless series past an operating station, said pads being positioned closely adjacent to each other except at the operating station where they are separated to provide a space so as to permit the introduction of a sole and shoe, gages for positioning a sole and shoe relatively to each other on a pad at the operating station, a pressure-receiving abutment at the bottom of each pad for clamping a sole and shoe on an adjacent pad, mechanism for moving each pad when above the operating station into shoe-clamping position relatively to a pad at said station, driving mechanism for effecting progression of the series step by step to present the successive pads in turn at said operating station, and mechanism acting automatically to withdraw the positioning gages from engagement with the sole and shoe before each progressive movement of the series is effected.

83. A machine for cement attaching soles to shoes having, in combination, a plurality of pads each constructed and arranged to receive a sole

- and shoe and positioned for progression in an endless series, said pads being mounted in pad boxes which are located closely adjacent to each other except at one point where they are separated to provide a space for the introduction of a sole and shoe, pressure-receiving abutments on the bottom of each pad box for clamping a sole and shoe on the next pad, gages operable to position a sole and shoe on a pad at an operating station and to hold them in said position until they are clamped on said pad, driving mechanism for effecting progression of the pads to present each pad in turn at the operating station, and means constructed and arranged to withdraw the positioning gages from engagement with the sole and shoe before progressive movement of the pads is effected. 80
84. A machine for cement attaching soles to shoes having, in combination, a fixed shaft, a plurality of pads arranged each to receive a sole and shoe and mounted for rotation in an endless series about said shaft, said pads being positioned closely adjacent to each other except at one point in the series where a space is provided to permit the introduction of a sole and shoe, pressure-receiving abutments for clamping a sole and shoe on each pad, positioning gages for locating a sole and shoe in a predetermined position before they are clamped on said pad, driving mechanism for effecting rotation of the series, and means for withdrawing the positioning gages from engagement with the sole and shoe so that said gages will not interfere with the rotation of the series. 85
85. A machine for cement attaching soles to shoes having, in combination, a plurality of pads each arranged to receive and apply pressure to a sole and shoe, said pads being mounted for progression in an endless series and being positioned closely adjacent to each other except at an operating station where a space is provided to permit the introduction of a sole and shoe, means for clamping a sole and shoe on each pad, a plurality of gages for positioning a sole and shoe mounted on a pad at the operating station, said gages being movable into and out of operative position over the pad at said station, driving mechanism for effecting progressive movement of the series step by step to present each pad in turn at the operating station, and means constructed and arranged to return the positioning gages to inoperative position before progressive movement of the series is effected. 90
86. A machine for cement attaching soles to shoes having, in combination, a plurality of pads each arranged to receive a sole and shoe and mounted for progressive movement in an endless series, said pads being positioned closely adjacent to each other except at an operating station where a space is provided to permit the introduction of a sole and shoe, a plurality of gages for positioning a sole and shoe on a pad at the operating station, said gages being constructed and arranged to hold the sole and shoe in a predetermined position relatively to each other on said pad, pressure-receiving abutments for clamping a sole and shoe on each pad, mechanism for moving said abutments into clamping relation to the shoes on said pads, latches for securing said abutments in shoe-clamping position relatively to the pads, driving mechanism for effecting a step-wise movement of the series to carry one pad away from the operating station and to move another pad into said station, and means constructed and arranged to return the positioning 95
- gages to inoperative position prior to the step-wise movement of the series so that said gages will not interfere with the movement of the pads into and away from the operating station. 100
87. A machine for cement attaching soles to shoes having, in combination, a plurality of pads arranged each to receive and apply pressure to a sole and shoe, said pads being mounted in pad boxes for progression in an endless series, pressure-receiving abutments on the bottom of each pad box for clamping a sole and shoe on an adjacent pad, positioning feelers constructed and arranged to engage and position a sole and shoe mounted on a pad at the operating station, said feelers being movable into and out of operative position over said pad, mechanism acting automatically to move the positioning feelers out of operative position over said pad, a clutch for effecting progressive movement of the series step by step to present each pad in turn at the operating station, and means whereby said clutch is tripped to effect progressive movement of the series subsequently to the operation of the mechanism for moving the positioning feelers out of operative position, so that the feelers will be removed from the path of the progressive movement of the series. 105
88. A machine for cement attaching soles to shoes having, in combination, a plurality of hollow pads mounted in pad boxes and arranged each to receive and apply pressure to a sole and shoe, said pad boxes being mounted for progression in an endless series, pressure-receiving abutments on the bottom of each pad box for clamping the sole and shoe on an adjacent pad, a plurality of feelers for engaging and positioning a sole and shoe on a pad at the operating station, said positioning feelers being movable into and out of operative position over successive pads at said operating station, mechanism actuated by a clutch for returning the positioning feelers to their inoperative position, a second clutch for effecting progressive movement of the series step by step to present other pads in turn at the operating station, and means whereby the second clutch is tripped a predetermined time after the first clutch has been tripped so that the positioning feelers will have been returned to their inoperative position before progressive movement of the series is effected. 110
89. A machine for cement attaching soles to shoes having, in combination, a stationary shaft, a plurality of arms mounted to rotate about said shaft, pads mounted on said arms and arranged each to receive a sole and shoe, means for clamping a shoe and sole on each pad, latches for connecting each arm to an adjacent arm, and mechanism for releasing the latches to disconnect an arm from its adjacent arm, said mechanism comprising a pivoted lever provided at one end with a counter-weight whereby said lever is held normally in its inoperative position. 115
90. A machine for cement attaching soles to shoes having, in combination, a horizontal shaft, a plurality of arms radially mounted to rotate in a vertical plane about said shaft and arranged in an endless series closely adjacent to each other except at an operating station where a space is provided in the series to permit the introduction of a sole and shoe, yieldable pads mounted on said arms and arranged to receive and apply pressure to a sole and shoe, abutments on the under side of each arm for clamping a shoe on the pad of an adjacent arm, latches on the arms for connecting each arm to an adjacent arm, and mechanism for releasing the latches to disconnect an arm 120

from its adjacent arm, said mechanism being constructed and arranged to move said arm into shoe clamping position relatively to an arm at the operating station and including a pivoted lever provided at one end with a counter-weight whereby said lever is held normally in its inoperative position.

91. A machine for cement attaching soles to shoes having, in combination, a stationary horizontal shaft, a plurality of arms arranged to rotate about said shaft, pads mounted on said arms and adapted each to receive a sole and shoe, pressure-receiving abutments on each arm for clamping a shoe on the pad of the next arm, and a lever constructed and arranged to move the arms successively into shoe-clamping position, each relatively to the next arm, said lever being adapted to support the arms successively and having at one end a weight sufficient to counteract the weight of the lever and one of the arms.

92. A machine for cement attaching soles to shoes having, in combination, a stationary horizontal shaft, a plurality of arms radially mounted to rotate in a vertical plane about said shaft and arranged in an endless series closely adjacent to each other except at an operating station where a space is provided to permit the introduction of a sole and shoe, flexible pads mounted on said arms and arranged each to receive and apply pressure to a sole and shoe, pressure-receiving abutments on the under side of each arm for clamping a shoe on the pad of the next arm, and treadle-operated mechanism for moving each arm in turn through said space into shoe-clamping position relatively to an arm at the operating station, said mechanism comprising a pivoted lever provided with a lug for supporting the successive arms and having at one end a counter-weight for holding the lever and the successive arms normally in their inoperative positions.

93. A machine for cement attaching soles to shoes having, in combination, a stationary horizontal shaft, a plurality of adjacent arms radially mounted to rotate in an endless series about said shaft, pads mounted on said arms and arranged each to receive and apply pressure to a sole and shoe, a space being provided between adjacent arms at one point in the series to permit the introduction of a sole and shoe, pressure-receiving abutments on the under side of each arm for clamping a shoe mounted on the pad of an adjacent arm, latching means on each arm for automatically latching it in shoe-clamping position relatively to an adjacent arm, and treadle-operated mechanism for moving each arm downwardly through said space until it latches in shoe-clamping position relatively to said adjacent arm, said mechanism comprising a pivoted lever provided at one end with a counter-weight sufficient to overbalance both the lever and one of the arms and having a lug which acts to support each arm during its downward movement.

94. A machine for cement attaching soles to shoes having, in combination, a plurality of pads arranged each to receive a sole and shoe and mounted for progression in an endless series past an operating station, pressure-receiving abutments for clamping a sole and shoe on each pad, a plurality of feelers movable into and out of operative position over a pad at the operating station for engaging a sole and shoe and positioning them on said pad, mechanism for moving said positioning feelers out of operative posi-

tion to permit progression of the series, and means constructed and arranged to prevent operation of said mechanism until after a sole and shoe have been clamped on the pad at the operating station.

95. A machine for cement attaching soles to shoes having, in combination, a plurality of pads arranged each to receive a sole and shoe and mounted for progression in an endless series past an operating station, pressure-receiving abutments at the bottom of each pad for clamping a sole and shoe on an adjacent pad, means movable into and out of operative position over a pad at the operating station for positioning a sole and shoe on said pad, treadle-operated mechanism for moving said abutments into shoe-clamping position relatively to a pad at the operating station, driving mechanism for effecting progression of the series step by step to present the other pads in turn at said operating station, power-operated mechanism for moving the positioning means out of operative position to permit progression of the series, and means constructed and arranged to prevent tripping of said power-operated mechanism until after the pressure-receiving abutments have been moved into shoe-clamping position relatively to the pad at the operating station.

96. A machine for cement attaching soles to shoes having, in combination, a plurality of pads arranged each to receive a sole and shoe and mounted for progression in an endless series past an operating station, positioning gages movable into and out of operative position over successive pads for positioning soles and shoes respectively on said pads, a plurality of abutments mounted under each pad for clamping a sole and shoe on an adjacent pad, means for moving a pad above the operating station to bring the abutments into shoe-clamping position, relatively to a pad at said station, means for effecting stepwise progression of the series to present the other pads in turn at said operating station, power-controlled mechanism acting automatically to withdraw said positioning means from their operative position over the pad at the operating station before progressive movement of the series is effected, and means constructed and arranged to prevent operation of said mechanism until after the abutments under the pad above the operating station have been moved into shoe-clamping position relatively to the pad at said operating station.

97. A machine for cement attaching soles to shoes having, in combination, a series of pad boxes provided with pads arranged each to receive a sole and shoe and mounted for progression past an operating station, a plurality of feelers movable into and out of operative position over a pad box at the operating station for positioning a sole and shoe on the pad of said pad box, means on the bottom of each pad box for clamping a sole and shoe on an adjacent pad, means for moving a pad box into shoe-clamping position relatively to the pad in the pad box at the operating station, means for effecting progression of the series step by step to present the other pad boxes of the series successively at said operating station, means actuated by a clutch for automatically withdrawing said feelers from their operative position over the pad box at the operating station before progressive movement of the series is effected, and a safety device constructed and ar-

- ranged to prevent the operator from tripping the clutch to withdraw the feelers until after a pad has been moved into shoe-clamping position relatively to the pad box at the operating station. 5
98. A machine for cement attaching soles to shoes having, in combination, a fixed shaft provided with a fluid-pressure conduit, a plurality of arms mounted on the shaft for movement together as a unit and for limited movement relatively to each other, a hollow pad on each arm, said pads being arranged to be presented successively at an operating station by movement of the arms as a unit, a fixed valve member having an inlet port communicating with said conduit, and a rotary valve member connected to one of the arms and having bores corresponding in number to the number of arms, each bore communicating with the pad on its corresponding arm and being arranged to communicate with the inlet port when that arm is at the operating station, an arm adjacent to said arm being movable relatively to said arm while the rotary valve member remains at rest, and the bore on said adjacent arm being brought into communication with the inlet port by the next movement of the arms as a unit. 10
99. A machine for cement attaching soles to shoes having, in combination, a fixed shaft provided with a fluid-pressure conduit, a plurality of arms mounted on the shaft for movement together as a unit and for limited movement relatively to each other, a flexible hollow pad on each arm, said pads being arranged to be presented successively at an operating station by movement of the arms as a unit, a fixed valve member having an inlet port communicating with said conduit, a rotary valve member connected to one of the arms and having bores corresponding in number to the number of arms, each bore communicating with the pad on its corresponding arm and being arranged to communicate with the inlet port when that arm is at the operating station, mechanism for rotating an arm relatively to an arm at the operating station while the rotary valve member remains at rest, and means for moving the arms as a unit to present the rotated arm at the operating station, said movement acting also to rotate the rotary valve member to bring the bore for said arm into communication with the inlet port. 15
100. A machine for cement attaching soles to shoes having, in combination, a fixed shaft provided with a fluid-pressure conduit, a plurality of adjacent arms mounted on the shaft for movement together as a unit and for limited movement relatively to each other, a flexible hollow pad on each arm, said pads being arranged to be presented successively at an operating station by movement of the arms as a unit, a fixed valve member having an inlet port communicating with said conduit, a rotary valve member connected to one of the arms and having bores corresponding in number to the number of arms, each bore communicating with the pad on its corresponding arm and each bore except the bore for the arm to which the rotary valve member is connected being located a predetermined distance in advance of its corresponding arm, means for moving each of the last mentioned arms relatively to an adjacent arm while the rotary valve member remains at rest to position said arm a predetermined distance in advance of its bore in the rotary valve member, and means for moving the arms as a unit to present each arm in turn at the operating station, this movement acting also to rotate the rotary valve member to such an extent that the bore for each arm is brought into communication with the inlet port as that arm is presented at the operating station. 20
101. A machine for cement attaching soles to shoes having, in combination, a fixed shaft provided with a fluid-pressure conduit, a plurality of adjacent arms provided with hollow flexible pads arranged each to receive a sole and shoe, said arms being mounted on the shaft for movement together as a unit to present the pads in turn at an operating station and being arranged for limited movement relatively to the other arms to clamp a shoe on the pad of an adjacent arm, a fixed valve member having an inlet port communicating with said conduit, a rotary valve member connected to one of the arms and having bores corresponding in number to the number of arms, each bore being arranged to communicate with the pad on its corresponding arm and each bore except the bore for the arm to which rotary valve member is connected being located a predetermined distance in advance of its corresponding arm, means for moving each of the last mentioned arms relatively to the other arms to clamp a shoe on the pad of the next arm while the rotary valve member remains at rest, this movement causing each of said arms in turn to assume a position which is a predetermined distance in advance of its bore in the rotary valve member, and means for moving the arms as a unit to present each arm in turn at the operating station, this movement being sufficient to cause the rotary valve member to advance until the bores for said arms are in communication with the inlet port. 25
102. A machine for cement attaching soles to shoes having, in combination, a fixed shaft provided with a fluid-pressure conduit, a plurality of adjacent arms provided with hollow flexible pads arranged each to receive a sole and shoe, said arms being mounted on the shaft for rotation together as a unit to present each pad in turn at an operating station and for limited rotation relatively to each other, a fixed valve member having an inlet port communicating with said conduit, a rotary valve member connected to one of the arms and having bores corresponding in number to the number of arms, each bore being arranged to communicate with the pad on its corresponding arm and being located to communicate with the inlet port when its corresponding arm is at the operating station, and means for rotating the arm to which the rotary valve member is connected to bring said arm into shoe clamping position relatively to an arm at the operating station, the bore for the arm then at the operating station being provided with a circumferential groove to permit communication with the inlet port after movement of the arm to which the rotary valve member is connected rotates said member, thereby causing said bore to change position relatively to the inlet port. 30
103. A machine for cement attaching soles to shoes having, in combination, a fixed shaft provided with a fluid-pressure conduit, a plurality of adjacent arms provided with hollow flexible pads arranged each to receive a sole and shoe, said arms being mounted on the shaft for rotation together as a unit to present the pads 35

successively at an operating station and each arm being arranged for limited rotation relatively to the other arms to clamp a shoe on the pad of an adjacent arm, a fixed valve member having an inlet port communicating with said conduit, a rotary valve member connected to one of the arms and having bores corresponding in number to the number of arms, each bore being arranged to communicate with the pad on its corresponding arm and each bore except the bore for the arm to which the rotary valve member is connected being located a predetermined distance in advance of its corresponding arm, means for rotating each of the last-mentioned arms to clamp a shoe on the pad of an adjacent arm while the rotary valve member remains at rest, thereby moving said arms a predetermined distance in advance of their corresponding bores in the rotary valve member, and means for rotating the arms as a unit to prevent each arm in turn at the operating station, said means acting also to rotate the rotary valve member so that as each arm is presented at the operating station the bore for that arm is brought into communication with the inlet port, the rotation of the arm to which the rotary valve member is connected, to bring that arm into shoe-clamping position relatively to an arm at the operating station, causing the rotary valve member to rotate until the bores assume their original position a predetermined distance in advance of their corresponding arms.

104. A machine for cement attaching soles to shoes having, in combination, a fixed shaft pro-
